UNITED STATES PATENT OFFICE.

BASIL M. WILKERSON, OF BALTIMORE, MARYLAND, ASSIGNOR TO THE S. S. WHITE DENTAL MANUFACTURING COMPANY, OF PHILADELPHIA, PENNSYLVANIA.

DENTAL CHAIR.

SPECIFICATION forming part of Letters Patent No. 642,405, dated January 30, 1900.

Application filed July 21, 1899. Serial No. 724,662. (No model.)

To all whom it may concern:

Be it known that I, BASIL M. WILKERSON, a citizen of the United States, residing in the city of Baltimore and State of Maryland, have 5 invented certain new and useful Improvements in Dental Chairs; and I do hereby declare the following to be a full, clear, and exact description of the invention, such as will enable others skilled in the art to which it app- 10 pertains to make and use the same.

My invention relates to dental chairs; and it consists in certain improvements principally in the back and foot rest sections thereof.

The object of my present invention is to im- 15 prove some of the sections of the dental chair shown in United States Letters Patent No. 581,670, granted to me April 27, 1897.

In the accompanying drawings, which show a suitable embodiment of my present improve- 20 ments, Figure 1 is a view in side elevation of a dental chair, showing my improved leg and foot rest section in its lowest as well as its highest position and with the back-rest section broken away. Fig. 2 is a top or plan view of 25 the dental chair with the back-rest section and the upholstered seat-pad omitted. Fig. 3 is a similar view with the leg and foot rest section omitted and also showing a somewhat modified seat-frame. Fig. 4 is a view in ver- 30 tical central section of the chair with the base or supporting portion omitted and with a portion of the back-rest section and a portion of the leg and foot rest section also omitted. Fig. 5 is a view in rear elevation of the main con- 35 trolling-rod of the leg and foot rest section de- tached. Fig. 6 is a view in rear elevation of my improved back-rest section. Fig. 7 is a central vertical sectional view of said back- 40 rest section, showing a portion of the seat- frame of the chair to which said back-rest sec- tion is attached. Fig. 8 is a view in side ele- 45 vation of a modified form of foot-rest. Fig. 9 is a view, partly in plan and partly in hori- zontal section, of a modified form of rock- 50 shaft for actuating the pawl of the leg and foot rest section. Fig. 10 is a detail sectional view showing one of the recesses for the side arms of the footboard-supporting frame.

That portion of the chair usually termed the 50 "foot-rest section" comprises a footboard,

platform, or leg-rest suitably connected to the seat-frame of the chair and a foot-rest proper carried by said footboard or platform.

The footboard or platform in the present instance, as in my before-mentioned patent, 55 No. 581,670, is capable of being raised and lowered relatively to the seat of the chair to accommodate persons of different stature. It is also capable of being elevated to a level with the seat-section of the chair and is main- 60 tained at all times practically in parallelism with said seat, so that when the footboard or platform is raised to the level of the seat it will form practically an extension thereof, and when in such position it comes into play 65 as a leg-rest. The back-section and the head- rest section (which latter section is not here- in shown) are likewise capable of being ad- justed to a level with said seat-section of the chair, whereby when all the sections of the 70 chair-body are brought into alinement the chair is virtually transformed into what is tantamount to a couch, or the "anesthetic" position, as it is called by dentists.

For the purpose of convenience all positions 75 of the back and the footboard when the same are not in alinement will herein be referred to as the "operating" positions, because these positions provide only for dental operations. The positions of these parts when in aline- 80 ment or in approximate alinement will be re- ferred to as the "anesthetic" position, because such position meets the requirements and in- cidents of anesthesia.

As the foot-rest carried by the footboard or 85 platform normally occupies a position above the level of said footboard or platform, it is obviously desirable when the chair is tempo- rarily transformed into a couch, as above in- dicated, that the foot-rest should also assume 90 an inoperative position in alinement with the other sections of the chair-body or drop to or below the level of the footboard, where it will be out of the way and not interfere with the feet of a person under the influence of an an- 95 esthetic. Besides generally improving the construction of the footboard and its operating mechanism I have also provided mechanism whereby whenever the footboard is elevated to its uppermost position the foot-rest, as just 100

stated, is caused to automatically drop to a level with the footboard and whenever the footboard is lowered the foot-rest automatically assumes its normal operative position.

5 I will first proceed to describe the improved leg and foot rest as follows: Curved side arms A A, constituting the supporting-frame of the footboard, are hinged or pivoted at or near their upper ends at a a to the opposite inner 10 sides of the seat-frame B of the chair, near the front of said seat-frame. The side arms are shown as being connected by a central plate, screen, or apron A', which may be cast integral with said arms or made separate 15 therefrom, as may be desired. A footboard or platform C is hinged at its inner end to the lower end of the side arms A A at a' a'. A foot-rest D is carried at the outer end of the footboard and is pivoted thereto by way of its 20 side arms D' D' at d d, the foot-rest being adapted to project above the footboard at all times save when the footboard is in its uppermost position on a level with the seat of the chair or when it is independently dropped 25 to or below the level of the footboard, as will be hereinafter explained. A supplemental foot-rest D² may be pivoted by way of its side arms D³ D³ to the outer end of the foot-rest at d' d' and is capable of being rocked into 30 either of two operative positions nearer to or farther away from the chair-seat. A controlling-rod E, preferably triangular in shape and of skeleton form and which will be herein referred to as the "main" controlling-rod, is 35 pivoted at its upper broad end at e e to the lower ends of brackets E' E', secured to the inner opposite sides of the seat-frame B, and at its lower end the main controlling-rod is pivotally connected at e' to the lower end of a link E², 40 pivotally connected at its opposite end to the pivot-rod a', connecting the side arms A A and the footboard. The distance between the pivots a and e is the same as the distance between the pivots a' and e'. Notched lugs 45 C' C', depending from the inner end of the footboard, are adapted to engage the pivot-bolt e', which unites the main controlling-rod and the link E². Thus the main controlling-rod may be said to be pivotally connected to 50 the footboard at the point e', and the construction is such that the parallelism of the footboard relatively to the chair-seat is preserved in whatever position of vertical adjustment said footboard may be placed. At 55 the same time, owing to the peculiar construction of the pivotal connection between the main controlling-rod and the footboard, the latter may be folded up against the supporting-frame and the foot-rest turned over and 60 down upon the chair-seat without disturbing the pivotal connection between the supporting-frame and main controlling-rod and the footboard. The purpose of this adjustment is chiefly to enable the chair to be conveniently packed for transportation and also for 65 moving the footboard out of the way when desired. When the footboard and foot-rest

are folded up, as just described, the notched lugs C' C' leave their bearing on the pivot e', which is held in proper position by the link 70 E², so that when the footboard is again lowered to its operative position the notched lugs will necessarily find their proper bearings.

A secondary controlling-rod F is located beneath the footboard and is sustained in 75 proper horizontal position and is adapted to have a slight endwise-sliding movement at or near its inner end in a stirrup C² on the under side of the footboard. The secondary controlling-rod has pivotal connection at its 80 outer end with the foot-rest D, a short distance below its pivotal connection d with said footboard, by way of a lug or lugs d² on said foot-rest. The inner end of the secondary controlling-rod is shown as being enlarged to 85 form a head F', adapted to bear against a rounded projection E³ of the main controlling-rod, said projection extending a short distance forward of the pivot e' of said main controlling-rod. By this construction it will 90 be seen that as the head of the secondary controlling-rod bears against the projection E³ of the main controlling-rod the foot-rest is caused to normally project above the surface of the footboard in operative position, 95 that when the footboard is raised to the level of the chair-seat to constitute a leg-rest, as before described, the movement of the projection E³ permits the secondary controlling-rod to move inwardly, whereby the foot-rest 100 is caused to drop to or below the level of the footboard to its inoperative position, and that when the footboard is lowered the projection E³ acts upon the secondary controlling-rod to cause the foot-rest to automatically 105 resume its operative position above the level of the footboard. This construction also allows of the footboard being folded up, as before described, the head of the secondary controlling-rod being free to leave the projection 110 E³ when the footboard is folded and being assured of coming in proper contact with this projection when the footboard is lowered again.

In addition to automatically raising and lowering the foot-rest relatively to the footboard by movement of the latter I have also provided means for enabling the foot-rest to be dropped to or below the level of the footboard independently of the movement of said footboard and in whatever position the same 115 may occupy. The preferred manner of accomplishing this is as follows: Instead of pivoting the forward end of the secondary controlling-rod F directly to the lug or lugs d² of the foot-rest I have provided a toggle-connection, as follows: The lugs d² are on opposite sides of the center of the foot-rest and a pivot-rod G passes through them. Pivoted upon said rod G, near the lugs d², are links G', through the opposite ends of which passes 120 a rod G², the forward forked end of the secondary controlling-rod being pivoted to said rod G². When the foot-rest is in its operative 125 position above the footboard, as shown in the

lower footboard, Fig. 1, the toggle connection is straightened out, the links G resting against the under side of the secondary controlling-rod, and the foot-rest cannot be moved downwardly. By slightly depressing the secondary controlling-rod by means of its operating-handle F² the toggle connection is broken or opened and the foot-rest is permitted to drop below the upper surface of the footboard into an inoperative position, as shown in the upper footboard, Fig. 1. A coiled spring H, connecting the footboard and the secondary controlling-rod, serves to assist in restoring the foot-rest to its upright operative position and to return the toggle to its closed position, which may be accomplished by simply grasping the foot-rest and lifting it. A rubber plug or plugs f may be secured upon the foot-board, and when the foot-rest drops the lugs d² strike against these plugs, whereby all noise and jar are prevented. The object in thus dropping the foot-rest below the upper surface of the footboard when the same is in its lowest or medium positions, or, in other words, when the footboard is in any of its operating positions, is to place it beyond the reach of the feet of a patient seated in the chair in order to prevent the patient from kicking or bringing undue pressure to bear upon the foot-rest when undergoing painful operations or when under the influence of an anesthetic. The operating-handle F² of the secondary controlling-rod may be depressed to drop the foot-rest either by hand or foot, as desired.

In Fig. 8 I have shown a modification of the connection between the footboard and foot-rest for permitting the latter to be dropped and in which the toggle-lever is omitted. This connection may be described as follows: Lugs d² are formed on the foot-rest, as before, and are connected by a rod d³. The outer ends of the secondary controlling-rod F are formed with lower notches f', upper notches f², and suitable cam-surfaces, as shown in the drawings. When the rod d³ rests in the lower notches f', the foot-rest is in its upright operative position. By depressing the secondary controlling-rod F, as before explained, the lower notches f' will leave the rod d³ and the foot-rest will drop until the rod d³ comes to rest in the upper notches f², the foot-rest being thus held in its inoperative position on or below the level of the footboard. The foot-rest may be restored to its normal operative position by simply lifting it, as before, until the rod d³ rests in the lower notches f'. It will be understood that the spring H should be employed, as in the preferred form. The rod d³, acting upon the cam-like surfaces of the notched secondary controlling-arm, provides for an easy and gradual stopping of the foot-rest, which may thus be dropped without shock or jar and without the employment of the rubber plugs f. (Shown in Fig. 1.)

It will of course be understood that with the herein-described organization of footboard and foot-rest the foot-rest is automatically

placed in an inoperative position whenever the footboard is moved to its uppermost or anesthetic position and that the foot-rest may also be placed in a similar inoperative position when desired even when the foot-board is in its lowest or any of its operating positions. Obviously this latter adjustment of the foot-rest may be used in an organization in which the automatic movement of the foot-rest is omitted.

The footboard may be locked and sustained in any position to which it may be vertically adjusted by means as follows: A pawl I, pivoted to or between lugs or brackets a², projecting from the central plate or screen A' of the footboard-supporting frame, is adapted to engage with the teeth of a ratchet-plate E⁴, connected to or formed with the main controlling-rod E. A weighted arm or extension I' of the pawl serves to normally hold the pawl in engagement with the ratchet-plate. The pawl is keyed upon a rock-shaft I², having bearing at one end in said lugs or brackets a² and projecting to one side of the supporting-frame, in which its opposite end has bearing. An operating pedal or handle J is provided for the rock-shaft I² and is located on the outside of the footboard-supporting frame. Instead of securing the operating-handle directly upon the rock-shaft I², upon which the pawl is keyed, I prefer to key it upon another rock-shaft J', parallel with the rock-shaft I² and having bearing in a projection a³ of the side frame A. A lever J², keyed upon the rock-shaft J', is connected with a lever I³, keyed upon the rock-shaft I², by means of a link J³, whereby the movement of the operating-pedal may be transmitted to the pawl I. The operating-pedal or handle J, which extends on opposite sides of the rock-shaft J', may be operated either by the hand or foot and serves as the means for actuating the pawl and also for raising and lowering the footboard.

The weight of the footboard and parts carried thereby is counterbalanced by a coiled spring K, which is connected at one end to a projection E⁵ on one of the brackets E' and at its opposite end is connected to the main controlling-rod E. The tendency of this spring is to pull the footboard upwardly, whereby the same may be raised and lowered with comparative ease.

When it is desired to raise the footboard, the operator's foot or hand is placed upon the operating-handle of the pawl J and a slight pressure upon the inner end of said handle serves to rock the pawl out of engagement with the ratchet and further downward and forward pressure upon the handle will elevate the footboard. Upon relieving the handle of pressure the pawl, owing to the action of its weighted arm, will immediately engage the ratchet and lock the footboard in any position to which it may have been elevated. To lower the footboard, the pawl is tripped, as before, and the footboard allowed to descend

to the desired position. It will be observed that the operating-handle is located at or near the bottom of the footboard-supporting frame, practically on a level with the footboard, in 5 convenient reach of the operator's foot and that when it is desired to but slightly change the vertical position of the footboard it can most conveniently be accomplished by means of the said operating - handle. Obviously, 10 however, the footboard may be elevated to any desired point by grasping it and lifting it bodily without operating the controlling-lever.

Owing to the particular connection between 15 the pawl I and its operating handle or pedal, the pivot of said handle or pedal is located more to the rear of the pivotal connection a between the supporting-frame and the seat-frame when the footboard is in its lowest position than would be the case were said handle or pedal secured directly upon the rock-shaft I² of the pawl. In this way a greater leverage is attained and the footboard may be elevated with greater ease. A similar result 20 may be attained by the modified construction shown in Fig. 9, in which the link J³ is dispensed with and the pawl I is carried on the same shaft J⁴ to which the operating handle J is secured, said shaft being disposed 25 obliquely relatively to the side arms A A, as shown.

The side arms A A of the footboard-supporting frame are preferably extended, as at 30 A², a short distance above the pivotal connection a of these arms with the seat-frame B, the object of this being to cover up the space which would otherwise be left between the said arms and the seat-frame when the footboard is elevated to its highest position. 35 The upper extensions A² of the side arms project into slots or recesses l in the wood base portion or frame L of the upholstered chair-seat L', which rests upon the metallic seat-frame B.

I will now proceed to describe my improved 40 back-rest as follows: The hinged connection between the back-supporting frame and the seat-frame is substantially the same as that shown and described in my before-mentioned 45 patent, as is also the locking mechanism for holding the back-supporting frame in any position to which it may be inclined; but the means for actuating said locking mechanism is different. The back-rest-supporting frame 50 N consists of two connected side or guide rails N' N', straight for the greater portion of their length, but at their lower ends curved in the arc of a circle to form an arc-shaped hinge member N². This arc-shaped hinge member N² is adapted to fit and move in or 55 upon a corresponding arc-shaped hinge member N³, fixed upon the seat-frame B. The arc-shaped hinge members are formed with suitable interlocking guide grooves and 60 tongues to guide and hold the parts in proper relation to each other. A pawl N⁴ is keyed upon a rock-shaft N⁵, journaled upon the

back-supporting frame in lugs n n, the pawl being provided with teeth for engaging a series of notches n' on the fixed hinge member 70 N⁶. A plate-spring N⁷, secured to the pawl N⁴ and bearing against a portion of the back-supporting frame, serves to keep the pawl engaged with the series of notches n', except when said pawl is purposely withdrawn therefrom. 75

The improved means for actuating the pawl N⁴ for withdrawing the same from locking engagement with the fixed hinge member for permitting the back-frame to be tilted back- 80 ward and forward is as follows: A bell-crank-controlling lever O is pivoted at o to one of the side rails N' of the back-supporting frame, near the top thereof, with its long arm O' projecting slightly beyond the side of the side 85 rail of the supporting-frame to which it is pivoted. To the inner or short arm O² of the controlling-lever is connected one end of a connecting rod or link O³, the opposite end of which is connected to an arm O⁴, keyed 90 upon the rock-shaft N⁶, to which the pawl N⁴ is also keyed. Pressure upon the long arm O' of the controlling-lever rocks its inner or short arm O², which motion is transmitted to the arm O⁴ by the connecting-rod O³, and the 95 pawl N⁴ is rocked downwardly out of engagement with the fixed hinge member.

It should be observed that the controlling-lever O of the back-frame-locking mechanism is located at a point where the back-frame is 100 grasped by the hands of the operator when it is desired to change the angle or inclination of the same and that when the back-frame is so grasped one hand of the operator 105 covers the projecting arm of the controlling-lever, and a slight and natural pressure of this hand upon the controlling-lever quickly releases the locking mechanism, and the back-frame may be rocked backward or forward, as desired. When the desired inclination or 110 adjustment of the back-frame has been attained, the operator simply releases his hold of the same and the locking mechanism automatically acts to instantly lock the back-frame in its adjusted position. Thus the adjustment of the back-frame may be quickly 115 and easily effected by inclining it forward as well as backward without the necessity of manipulating any handles, screws, or levers, save the rocking of the controlling-lever, 120 which, as before stated, may be performed by the same movement of the hand required for grasping and moving the back-frame.

A vertically-adjustable back-pad carrier or frame P is suitably mounted to be moved up 125 and down upon the back-supporting frame, and a back-pad P' is hinged to the top of said frame; but as the construction of these particular parts of the chair form no part of my present invention description of them is un- 130 necessary.

For the purpose of quickly and automatically elevating the footboard to its uppermost position when it is desired to place the chair

in its aforesaid anaesthetic position I have provided mechanism whereby when the back-rest section of the chair is lowered to a level with the chair-seat the footboard is automatically raised to a level with said seat. I am aware that such a movement is not broadly new; but I have devised novel and improved means for accomplishing it, which I will now describe.

- 10 A link R, passing from front to rear of the seat-frame of the chair, is pivoted at its forward end to the footboard-supporting frame a short distance below its pivotal connection a with the seat-frame B. Said link is shown 15 as being pivoted between lugs a^4 on the inner side of the central plate or screen A' of the footboard - supporting frame. The link is prevented from falling by means of a side lug r near its rear end resting and adapted to 20 travel upon the curved flange or ledge s of a guide-plate S, secured to the seat-frame. The rear extremity of the link is notched at r' for engagement with a stud n² on one of the side rails N' of the back-rest-supporting 25 frame, near the lower extremity thereof.

Without further description it will be apparent that the back-rest may be adjusted or rocked back and forth within certain limits to secure all necessary or desired "operating" positions without affecting or moving the footboard and that the footboard may likewise be raised and lowered to secure various operating positions without affecting the back-rest. The moment, however, the back 30 is lowered to or beyond the limit of its operating positions its stud n² comes in contact with the notched end of the link R, which transmits the continued downward movement of the back-rest to the footboard, whereby the 35 latter is raised to the level of the chair-seat simultaneously with the lowering of the back-rest to the level of said seat. After the back-rest has been moved to a level with the chair-seat and the lever O released, the back-rest 40 and of course the footboard are securely locked in position. When the back is again raised to the point where its operating positions begin, the footboard is automatically lowered to the beginning of its medium or 45 operating position, at which point the back and the footboard are again independently adjustable.

The guide S not only serves to prevent the link R from falling when its notched end is 50 not engaged by the stud n² of the back-rest, but it also maintains said link in the proper position to insure the contact or engagement of the stud and notched link in whatever position they may happen to be when it is desired to elevate the footboard by means of 55 the back-rest.

The number and arrangement of the teeth on the rock-plate E⁴ of the main controlling-rod is such that the pawl does not act after 60 the footboard has been elevated a certain distance—say about midway between its highest

and lowest positions. By this means the foot-board may be adjusted to and locked in any desired operating position of vertical adjustment from its lowest to its medium positions 70 in which it is to be used as a foot board or rest by its operating-treadle and locking-pawl; but after the footboard is raised to its highest position to form a leg-rest, as previously explained, it will freely move to its 75 medium position when the back-rest is raised to the beginning of its operating position.

As shown in Fig. 2, the seat-frame B of the chair is, as usual, journaled to rock about trunnions t t of a yoke or cross-head T, connected 80 to the upper end of a chair-body-supporting plunger U. In Figs. 3 and 4 I have shown an improved connection between the seat-frame and the yoke or cross-head. In this improvement instead of journaling the yoke 85 directly to the sides of the seat-frame, as is customary, it is journaled to trusses B' B', which extend from front to rear of the seat-frame near and substantially parallel with the sides of said frame. These trusses B' B' 90 are bowed or curved upwardly, as shown in Fig. 4, in order that their central portions, to which the yoke is journaled, may extend above the top of the seat-frame. The trusses are shown as being cast integral with the seat-frame, although, if desired, they may be made 95 separate and bolted to the seat-frame. This construction not only provides a stronger and more rigid seat-frame, but it permits of the use of a shorter yoke or cross-head, which obviously has less spring or yield than the comparatively long cross-heads now in common use. Moreover, this construction enables the trunnions to be located above the seat-frame B and between the frame L of the upholstered 100 seat L, thus elevating the trunnions and bringing them nearer the center of weight of the chair-body and patient, whereby the chair-body is more evenly balanced.

The dental chair herein shown and described represents but a single embodiment of my invention, together with some slight modifications; but it is obvious that my invention is susceptible of many variations without departing from the scope of my invention, and I therefore do not wish to be understood as being confined to the precise details of construction herein shown and described.

I claim as my invention—

1. The combination with the seat of a dental chair, of the footboard-supporting frame hinged thereto, the footboard hinged to the lower end of said frame, means for maintaining the parallelism of said footboard relatively to said seat when the former is vertically adjusted, a foot-rest carried at the outer end of the footboard and normally occupying a position above the level of the plane of the same, and means for automatically moving 125 the foot-rest into a position on a level with or below the upper surface of the footboard 130

when said footboard is moved into a position on a level with said seat, substantially as and for the purpose described.

2. The combination with the seat of a dental chair, of the footboard-supporting frame hinged thereto, the footboard hinged to the lower end of said supporting-frame, a foot-rest hinged to the outer end of said footboard and normally occupying a position above the level of the same, a main controlling-rod pivoted to said seat and to said footboard, a secondary controlling-rod pivoted to the main controlling-rod and to the foot-rest, whereby when the footboard is raised to the level of the seat, the foot-rest is automatically moved into a position on a level with the footboard, and means for locking the footboard in any position to which it may be adjusted, substantially as and for the purpose described.

3. The combination with the seat of a dental chair, of the footboard-supporting frame hinged thereto, the vertically-adjustable footboard hinged to the lower end of said footboard-frame, mechanism for locking the footboard in its vertically-adjusted position, and a lever located substantially on a line with the plane of said footboard for controlling said locking mechanism and by means of which the footboard may be raised and lowered, substantially as and for the purpose described.

4. The combination with the seat of a dental chair, of a footboard-supporting frame hinged thereto, a vertically-adjustable footboard hinged to the lower end of said supporting-frame, a controlling-rod pivoted to said seat and to said footboard, a rack upon said controlling-rod, and a rocking pawl carried by said supporting-frame, substantially as and for the purpose described.

5. The combination with the footboard of a dental chair, of a foot-rest pivoted to the outer end thereof, means for sustaining said foot-rest in an upright operative position above the level of said footboard, and means whereby said foot-rest may be caused to drop into an inoperative position to or below the level of said footboard, substantially as and for the purpose described.

6. The combination with the footboard of a dental chair, of a foot-rest pivoted to the outer end thereof, and a toggle-lever connection between said footboard and said foot-rest, whereby when the toggle-lever is straightened out the foot-rest is sustained in an upright operative position above the level of the footboard and when the toggle-lever is opened the foot-rest is permitted to drop to or below the level of the footboard into an inoperative position, substantially as and for the purpose described.

7. The combination with the seat of a dental chair, of a footboard-supporting frame hinged thereto, a footboard hinged to the lower end of said supporting-frame, a foot-rest pivoted to the outer end of said footboard, a main controlling-rod pivoted to said

chair-seat and to said supporting-frame, a secondary controlling-rod connected at one end with said main controlling-rod, and a toggle-lever connection between the opposite end of said secondary controlling-rod and said foot-rest, whereby when said toggle-lever connection is straightened out the foot-rest is normally sustained in an upright operative position above the level of said footboard and when said footboard is raised to its uppermost position on a level with said chair-seat the foot-rest is automatically moved to a position on a level with or below the surface of said footboard, and when said toggle-lever connection is opened or broken the said foot-rest drops to or below the level of the footboard independently of the movement of said footboard, substantially as described.

8. The combination, in a dental chair, of the footboard, the foot-rest pivoted to the outer end thereof and adapted to normally occupy an operative position above the level of said footboard, and a supplemental foot-rest pivoted to the outer end of said foot-rest, and adapted to be turned into two operative positions nearer to and farther away from the footboard, by rocking it about its pivotal connection with said foot-rest, substantially as and for the purpose described.

9. The combination, in a dental chair, of the metallic seat-frame, an upholstered seat fitted thereon, and provided with a wood base having slots or recesses in its opposite sides, a footboard and side arms forming the supporting-frame for said footboard and pivoted to said metallic seat-frame, said side arms extending a short distance above their pivotal connections with said metallic seat-frame, said extensions being adapted to enter the slots or recesses in the wood base of the upholstered seat when the footboard is in any of its low positions, substantially as and for the purpose described.

10. The combination, in a dental chair, of the seat, a back-supporting frame hinged thereto and adapted to be rocked vertically, means for locking said back-supporting frame in any position to which it may be rocked, and a controlling-handle pivoted to said back-supporting frame to rock transversely thereof, whereby said locking means may be controlled by moving said lever transversely of the back-supporting frame, substantially as and for the purpose described.

11. The combination, in a dental chair, of the seat, a back-supporting frame hinged thereto and adapted to be rocked vertically, an automatic lock for normally locking said back-supporting frame in any position to which it may be rocked, a controlling-lever for said lock pivoted to said back-supporting frame and having its handle projecting from the side thereof, whereby when the handle of said controlling-lever is pressed inward, the lock is released and the back-supporting frame is free to be rocked vertically, substantially as described.

12. The combination, in a dental chair, of the seat provided with a fixed arc-shaped hinge member having detent-notches therein, a back-supporting frame provided with an arc-shaped hinge member having sliding connection with said fixed hinge member, a pawl pivoted to said back-supporting frame and normally in engagement with the detent-notches of said fixed hinge member, a controlling-lever pivoted to said back-supporting frame near its upper end and having its handle projecting from the side thereof, and a connection between said pawl and said controlling-lever, whereby when the handle of the latter is pressed inward the pawl is disengaged from the notches of the fixed hinge member, substantially as and for the purpose described.

13. The combination, in a dental chair, of the seat, a vertically-adjustable footboard hinged to the front thereof, a foot-rest carried at the outer end of said footboard and normally occupying a position above the level of the same, a back-rest hinged to the rear of said seat-frame, and connections between said back-rest and said footboard and between said footboard and said foot-rest, whereby the back-rest and the footboard may be independently adjusted to various operating positions within certain limits, but when the back-rest is lowered to a level with the seat, the footboard is automatically elevated to a level with said seat and said back-rest, and the foot-rest is automatically lowered to or below the level of said footboard, to bring the back-rest, the seat, the footboard

and the foot-rest into alignment, substantially as and for the purpose described.

14. The combination, in a dental chair, of the seat, a vertically-adjustable footboard hinged to the front thereof, a back-rest hinged to the rear of said seat and adapted to rock vertically, both the back-rest and the footboard being capable of adjustment to a level with said seat, a link pivoted to the footboard and provided with a side lug, and having its rear end notched, a fixed guide-plate having a curved flange or ledge upon which the said side lug of the link rests and travels and a stud on the back-rest adapted to engage the notched end of said link, whereby when the back-rest is lowered to a level with the seat the foot-rest is thereby automatically elevated to a level with said seat, substantially as and for the purpose described.

55

15. The combination, in a dental chair, of the seat-frame, trusses extending from front to rear thereof and substantially parallel with the sides of said frame, said trusses also extending above the top of said frame, a chair-body-supporting plunger, and a yoke or cross-head connected to said plunger, the seat-frame being journaled to said cross-head by way of the trusses, the journals being located at a point above the level of the seat-frame, substantially as and for the purpose described.
